DESIGN FOR A CAN OPENER

Samuel A. McKittrick, Sandusky, Ohio

Application August 23, 1944, Serial No. 114,975

Term of patent 14 years

(Cl. D22—2)

To all whom it may concern:

Be it known that I, Samuel A. McKittrick, a citizen of the United States, residing at Sandusky, in the county of Erie and State of Ohio, have invented a new, original, and ornamental Design for a Can Opener, of which the following is a specification, reference being had to the accompanying drawing, forming part thereof.

In the drawing:

I claim:

The ornamental design for a can opener, as shown.

SAMUEL A. McKITTRICK.
